UNITED STATES PATENT OFFICE.

JOHN S. GILLIES, OF BROOKLYN, NEW YORK.

APPARATUS FOR MAKING CONCRETE PILES.

1,403,766.

Specification of Letters Patent. Patented Jan. 17, 1922.

Application filed October 18, 1916, Serial No. 126,241. Renewed May 18, 1921. Serial No. 470,608.

To all whom it may concern:

Be it known that I, JOHN S. GILLIES, a citizen of the United States, and resident of the borough of Brooklyn, city of New York, and State of New York, have invented certain new and useful Improvements in Apparatus for Making Concrete Piles, of which the following is a specification.

My invention relates to apparatus for 10 molding concrete piles in situ.

The object of my invention is to provide a metallic shell that may be driven with certainty and withdrawn from the ground after it is filled with concrete. A further 15 object is to provide a suitable mandrel to drive such a shell.

To accomplish these objects I provide a metallic shell split longitudinally from end to end, the edges of the split portion being 20 turned inwardly to form flanges. Normally the shell is open, and is closed against spring action, the purpose of which is to keep the ground in place around the opening and to facilitate withdrawal of the shell after it 25 is filled with concrete. A mandrel to cooperate with the shell is inserted therein and is provided with means for firmly holding together the interior flanges and at the same time expanding its sides so as to contact with 30 and support the entire interior surface of the shell during the driving. In driving this shell with a mandrel of such character, compression from without is not only provided against, but also the liability of the 35 mandrel to slip within the shell, which is impossible when the interior flanges of the latter are rigidly held from end to end. Devices for pulling the shell are also provided.

40 My invention is illustrated in the drawings, in which Fig. 1 is a perspective view of the shell in closed position, the lower portion being broken away; Fig. 2 is a similar view of the shell in open position; Fig. 45 3 is a longitudinal section of the shell and mandrel; Fig. 4 is a top view of the driving head; Fig. 5 is a view of the shell in section and the mandrel and head in elevation, the mandrel being in contracted position; Fig. 6 is an elevational view of the 50 shell, with driving head and point attached, and showing in dotted lines parts of the mandrel; Fig. 7 is a section on the line 7-7 Fig. 6; Figure 7^a is an enlarged view 55 of part of the section shown in Figure 7;

Fig. 8 is a longitudinal section, with a broken portion, on lines 8-8 Fig. 7, one of the wedges being shown and the mandrel being in expanded position; Fig. 9 is a similar view with the parts in contracted position; Fig. 10 is a perspective of the top portion of the last mentioned wedge, Fig. 11 is a similar view of the inside holding-plate for said wedge showing the upper part of the wedge in cross-section; Fig. 12 is a perspective view of another wedge, shown in Fig. 7, cooperating with the wedge shown in Figs. 7, 8, 9, 10 and 11; Fig. 13 is a perspective view of the inside holding plate for the wedge shown in Fig. 12; Fig. 14 is a 70 sectional view of the lower portion of the mandrel; Fig. 15 is a top view of a detail; Fig. 16 is a modified form of the shell shown in Figs. 1 and 2; Fig. 17 is a view partly in section and partly in elevation 75 of the shell and mandrel, with driving head and driving point, but with some of the details omitted; Fig. 18 is an elevational view of a modification of the wedge shown in Figs. 8 and 9; Fig. 19 is an elevational 80 view of parts used in driving a short shell and also showing guides on the driving head for the leaders of the pile driver to set in, omitted in other figures; Fig. 19^a is a plan view of the head and guides; Fig. 20 is a perspective of parts shown in Fig. 19; Fig. 21 is a perspective of a device attached to the top of a shell for pulling the latter 85 from the ground when filled with concrete, the lower end of the shell being broken 90 away; Fig. 22 is a similar view of parts shown in Fig. 21; Fig. 23 is a top view of another modification of the shell shown in Figs. 1 and 2, together with another form 95 of mandrel; Fig. 24 is a detached top view of the mandrel shown in Fig. 23; Fig. 25 is a top view of the same mandrel in a hexagonal shell; Fig. 26 is a perspective view of the parts shown in Fig. 23, showing one section partly removed from the mandrel; 100 Fig. 27 is a sectional view of the driving shoe used in connection with the mandrel last referred to; and Fig. 28 is a longitudinal section of said mandrel, with the lower portion broken away, and showing a driving 105 head connected thereto. Fig. 29 is still another form of an expanding mandrel.

Referring to the drawings in detail, and more especially to Figs. 1 and 2, 1 represents the driving shell, which is, preferably, 110

slightly tapered, and 2 the flanges formed by the longitudinal division of the shell and turning inwardly the edges along the same. In Fig. 2 these flanges are shown released 5 and the shell slightly expanded, due to the spring action of the shell, it having a tendency to open when its flanges are not confined. 3 indicates a tongue or strap of metal riveted, preferably, on the interior of 10 the shell and, passing through the junction of the flange with the side of the shell, is adapted to enter an opening at 4 at the junction of the other flange with the other side of the shell, thus preventing longitudinal 15 movement of one side of the shell relatively to the other side. It is obvious that if such a shell is securely held by its flanges to a mandrel during driving it will be held more rigidly than would be possible even 20 by an expanded mandrel in a shell without such flanges.

The preferred form of mandrel designed to cooperate with the shell just described is illustrated in Figs. 3, 5, 6, 7, 8, 9, 10, 11, 25 12, 13, 14, 15, 17 and 19, wherein 5 is an I beam detachably connected to the shoe 6. The latter is slotted at 6', as shown in dotted lines in Fig. 6, to permit the flanges of the outer shell to be run therethrough into position 30 on the mandrel, and it is also centrally bered at 7 for the pin 8 which has a threaded nut 9 at its lower end entering a recess at the lower end of the bored opening 7; the lower end of pin 8 being screw-threaded for the 35 reception of the nut 9. Pin 8 is split at its upper end to receive the web of the I beam to which it is connected by bolt 10. The I beam is selected not only for its ability to withstand driving strains, but also, on account of its shape, to keep the parts in position. The nut 9 is provided at the lower 40 end of pin 8 so that the pin 8 may be first connected at its split or bifurcated upper end with the web of the I-beam and the 45 shoe 6 then placed in position thereon, nut 9 being then screwed onto the lower end of the pin 8 to hold it there. It should be noted in this connection that the driving shell 1 includes, at its lower end, a cap 50 which, when the mandrel is in condition for use, encloses the shoe 6 and extends, at its upper end, beyond the same into meeting engagement with the lower edge of the main body of the shell 1. One purpose of this cap 55 is to prevent the entrance of earth into the lower end of the mandrel or the opening 7 in the shoe 6, and the purpose of the meeting engagement between the cap and the main portion of the shell is to provide for a 60 smooth outer surface on the shell 1 so that the downward movement of the latter will not be resisted by the earth through which it passes. The cap also encloses the lower end of the leaves 11 and 11', hereinafter de- 65 scribed, of the mandrel and thereby, and by

reason of its engagement with the shoe 6, aids the pin 8 in centering said shoe, or properly positioning it, with relation to said leaves and other parts of the mandrel.

The outer wall of the mandrel is cylindrical, and is divided into two semi-circular members or leaves 11, 11'. The leaf 11' has an inwardly turned flange 12 forming a jaw for a gripping device which will hereinafter be described. The inwardly-turned flange 75 12 has a right-angled top portion 13 fitting into the recess of the I beam. As expanded the mandrel is shown in dotted lines in Fig. 8 and as contracted in dotted lines in Fig. 9, the movement of the outer wall being effected principally by means of wedges.

The wedges are, preferably, two in number, although there may be further divisions of the parts if desired. The wedges are clearly shown in cross-section in Fig. 7, and are indicated in whole as 14, 14'. One of the wedges, 14, is shown in elevation in the sectional views of Figs. 8 and 9, and in Fig. 12 is a perspective view of the other wedge, 14'. The wedge 14, shown in Figs. 8 and 9, 90 is compound, being composed of a series of individual wedges having the shape of a cone in section, indicated at 15 in the drawings. Extending along each side of the wedge 14 are a series of wings 16 16' bearing against the sides of the wedges 15. It will be noted that these wings extend only about seven-eighths of the length of the wedges, leaving a space between the bottom of the wings and the top of the adjoining 95 wedges to permit the wedges to rise from the position shown in Fig. 8 to that shown in Fig. 9. In the upper one of the series of individual wedges are diverging slots 17, 17, and in the lower of the series are similar 100 slots, 18, 18. In each of the slots referred to and movable therein is a bolt 19 projecting from the leaves 11, 11' of the mandrel, into the inner plate hereinafter referred to, to which it is positively fixed. It may be 105 stated generally that downward movement of the individual wedges along the sides of the wings tends to expand the outer wall of the mandrel, while the downward movement of the bolts in the slots just referred to tends to contract the same, as will herein- 110 after more fully appear.

For more securely holding the wedge 14 in proper position, an inside plate 20 is provided, this being more fully shown in Figs. 120 7 and 11. This plate is securely bolted to the outer leaves 11, 11', and this is done so as not to interfere with the movements of either the wedge or outer leaves, by providing slots in connection with the bolt-holes where necessary to permit movement of the parts as desired. In Figs. 7, 8, 9 and 11 there is shown a bracket 21 having the form of a channel iron, one end of which, 21', abuts the outside of the wings 16 and assists in holding them and 125 130

the wedge in place, and the other end encloses the inner plate 20. This bracket 21 is bolted to the outside leaf 11' by bolt 22 which has movement in the slot 23 in the 5 inner plate, as shown in Fig. 11.

The outer leaf 11, the series of wings 16' and the inner plate 20 are connected positively by bolts, one of which is shown at 25. In the construction shown in Fig. 11 10 the bolts 19, 19' also extend through the inner plate, and a slot 26 in the inner plate permitting movement therein of the bolt 19', secured by nuts and washers, makes it 15 possible for the parts to expand, as will hereinafter more fully appear. This arrangement of bolts, and slots is repeated in the case of each individual wedge. A lip 27 extends from the top of the wedge 14 at right angles to the side, as shown in Fig. 10, 20 with bolt-holes 28, the purpose of the lip being to lift the wedge, through connections between it and the head when the mandrel is lifted by the head. The connections between the lip and head will hereafter be 25 described.

The form of the wedge just described may be varied, as shown in Fig. 18, where there is shown a wedge with straight inclined sides, intended to cooperate with guides with 30 similar sides. The bolts 19, 19' in the slots 18 act in all respects the same as those in the wedge above described.

The other wedge, 14', is shown in cross-section in Fig. 7 and in perspective in Fig. 35 12. It has a portion 28 forming the segment of a circle and a portion 29 at right angles thereto. The last named portion has two vertical slots 30, 31, indicated in dotted lines in Fig. 12. On the opposite side it 40 has individual wedges 32 and two longitudinally extending inclined slots 33. It also has a lip 34 at its top extending at right angles to its side. The lip is provided with bolt-holes 34'. The purpose of this lip, like 45 the one on the wedge 14, is to lift the wedge through connections between it and the head when the mandrel is lifted by the head, as will hereinafter more fully appear.

50 Bearing in mind that the wedge 14 has for its object the shifting of the outer leaf 11, it may be stated that the purpose of this wedge, 14', is to bear more directly upon the flanges of the outer shell by means 55 of an element interposed between the two, which latter will now be described.

A pair of jaws is formed for gripping the inwardly extending flanges of the outer shell by a piece of structural iron or steel 60 L shaped in cross-section and corresponding to and coacting with the part 12 of the outer leaf 11'. This L shaped member or jaw is indicated in the drawings at 12' and with the other jaw, 12, resembles the letter 65 T. Between the jaws 12 and 12' is a small

tapered or wedge shaped member 36, and the jaws and tapered member are connected by dowels 37 in such manner that the jaws will rock on the member 36 and grip the inner flanges of the outer shell when the 70 latter are interposed between them. The wedge 14' is connected to the jaw 12' by means of bolts 38 which pass through the vertical slots 30, 31 in the wedge and into a bar 39 which extends longitudinally of the 75 wedge. The bolts 38 are secured positively to the bar 39 but have free movement in the slots 30, 31.

The wedge 14' is further held in position by inner plate 40, the latter being shown in 80 cross-section in Fig. 7 and in perspective in Fig. 13. This inner plate 40 has a small turned-in portion 41, completely enclosing the side of the wedge, and on its inner side provided with wings 42 corresponding 85 to the individual wedges of the main wedge. The inner plate is securely bolted to the outer leaf 11 by bolts one of which is shown in Fig. 7 at 43. Bolts or studs 44 extending from the inside of the inner plate into the 90 inclined slots 33 and into the leaf 11 assist in holding the wedge 14' in position, and they also cooperate with the individual wedges and wings to move the wedge 14' back and forth laterally to and away from 95 the jaw 12'.

In order to assist in supporting the I beam, which is detachably connected to the shoe 6, a number of stays are provided, as shown in Fig. 3, consisting of a rod 45 having nuts 46 adjustable thereon by means of screw threads, and wires 47 running from the outer leaves of the mandrel to which they are secured and are connected to the rod 45 in any suitable manner, so that, by 100 manipulation of the nuts, the stays may be stiffened or made slack. In the drawing the wires are shown as running through the outside portions of the I beam, and openings are also shown in the web of the I beam for 105 more convenient manipulation of the nuts, but the stays can be otherwise secured, or wholly omitted.

In Fig. 15 there is shown in plan a disk 48 having two depressed portions 49, 49', into 115 which the lips of the two wedges 14, 14' are countersunk. The disk sits over the top of the I beam and inside and flush with the outer leaves of the mandrel, as clearly shown in cross-section in Fig. 3. The disk 120 is secured to the lips of the wedges by bolts 50 passing through holes 49' of the disk, 34' of the lip 34, and 28 of the lip 27, from which they pass through the head, as 125 shown in Fig. 4.

The disk is also provided with a central opening 51 for the pin 52 having a countersunk head 53. The lower end of the pin is bifurcated and is seated over the web of the I beam, so that one of the bifurcations 130

is on each side thereof. One of the bifurcations is clearly shown in Fig. 3, showing also a longitudinal slot 54 in the bifurcation, similar to one in the other bifurcation, and 5 a pin 55 in the upper portion of the slot, which pin passes through the web of the I beam into the slot of the opposite bifurcation. Both bifurcations are shown in cross-section in Fig. 7. This slot provides for 10 lost motion when the mandrel is lifted by the head, so that the wedges will be first lifted, and the flanges of the outer shell thereby released, before the mandrel itself is moved.

It will, therefore, appear that disk 48 has 15 manifold functions in its seat at the top of the mandrel. It not only lifts the wedges simultaneously through its connection with the head, but it tends to keep the top of the outer leaves of the mandrel (and consequently the top of the outer shell) stiff and thereby prevents them from bending or breaking.

The disk 48 is also provided with two 20 downwardly extending flanges 55', on opposite sides thereof, each flange having an opening 56 for locking with the head, as will hereinafter more fully appear.

A driving cap or head 57 is shown in Figs. 3, 4, 5, 6 and 17. The lower portion 58, 25 which is annular, embraces not only the mandrel, but the outer shell as well, and the three are secured to each other by keys 59 which are passed through openings provided therefor in the outer shell, the outer 30 leaves of the mandrel and the opening 56 in the downwardly extending flanges 55'. The head is also provided with an upper annular flange 60 containing a wooden block 35 for receiving the blows of the driving hammer. The driving head is also further provided with a lifting rope 61, which passes from side to side through suitable openings, and has lifting loops 62.

The shell and mandrel are represented in 40 the drawings (with the exception of Fig. 17) as tapered, but this invention may just as well be applied to straight shells and mandrels. Furthermore, while I have shown only two leaves to the mandrel one pair 45 of jaws and two wedges in the preferred form, the number of these parts may be increased, or the number of wedges may be decreased, or the I beam omitted, and still be within the spirit of my invention.

50 In Fig. 29 I have shown in cross-section how it is possible to increase the number of wedges. In this case the outer leaves of the mandrel are represented at 11^a, 11^b, and 11^c, and the wedges at 14^a, 14^b and 14^c. The 55 inside plates for holding the wedges in position are designated at 20^a, 20^b and 20^c. The jaws 12^a and 12^b for holding the flanges of the outer shell during the driving operation are pivoted at their inner ends at 63. Keys 60 65 59^a, 59^b and 59^c are provided for locking

the parts in position. The other parts must be understood to be the same as in the form explained at length.

The operation is as follows. Assuming that the disk 48 is properly in place under 70 the lips of the two wedges and bolted to the head, and that the bolt 52 is connected to the I beam 5, the mandrel is made ready for receiving the outer shell by the simple operation of lifting the mandrel by the head 75 by means of the lifting loops 61, 61 a foot or two off the ground, thereby lifting upwards the two wedges 14, 14', which, in turn, opens the jaws 12, 12'. The outer shell is then opened for wrapping the same around 80 the mandrel. It would be impracticable to do this with the top of the shell in the same plane with the top of the mandrel, as the diameter of the shell would be too small to permit its flanges to go between the jaws 85 of the mandrel. The shell is, therefore, wrapped around the mandrel somewhat lower down, where on account of its taper the diameter of the mandrel is smaller and where the flanges of the shell may be readily 90 inserted into the jaws of the mandrel and into the slot 6' of the shoe 6. From this place the shell may be readily pushed up into its proper position on the mandrel. A cap 6'' is then placed over the shoe 6, 95 to keep the dirt out of the slot 6'. The driving hammer is then lowered upon the head or driving cap with sufficient force to depress the wedges and until the openings through the opposite sides of the outer shell, 100 mandrel leaves and downwardly extending flanges of the disk 48 all register, when the keys 59, 59 are inserted, which lock the parts against movement from this position, wherein the outer shell is firmly held from 105 end to end by its flanges against longitudinal movement relatively to the mandrel, and also its entire interior surface is supported against compression from without. When 110 the outer shell has been driven to a sufficient depth, the keys 59, 59 are withdrawn, and the mandrel is lifted, as before, the effect of which is to simultaneously withdraw both wedges and release the inward flanges of 115 the outer shell from the jaws of the mandrel. The mandrel may then be withdrawn and the shell filled with concrete, the keys being replaced to lock the mandrel in position for receiving the shell. It may be stated, also, 120 that in the lifting of the mandrel, the wings 120 at the sides of the wedges, acting as stops to limit the movement of the wedges, assist in carrying the load.

After the shell has been filled with concrete, the shell itself may be left in the 125 ground or withdrawn by the apparatus to be described. This apparatus is shown in Figs. 21 and 22. Fig. 21 is a perspective view thereof, wherein 1 represents the outer shell, 2 the flanges of the same, and 63 is a 130

collar sitting inside the top of the shell where it is supported by clips 64. This inside collar also has guides 65 in which to manipulate the wedge 66. Cooperating with 5 the inside collar is the lifting line 67, having a slip knot 68 and loop 69 and supporting-clips 70. When the shell is ready for pulling, the parts are adjusted in the manner shown in Fig. 21. When lifting force 10 is applied to the lifting line 67, the inside collar 63, assisted by the wedge 66, supports the shell and prevents collapse where the lifting force is applied. The first upward movement of the shell will be a short one. 15 The lifting line is then slackened and the wedge 66 is forced deeper between the guides 65, thereby forcing the shell further apart. The lifting line is then taken up again and the shell is lifted further out of 20 the ground, the wedge 66 in the guides 65 in the meantime keeping the shell in the open position in which it was set, thereby facilitating its withdrawal from the ground.

In Fig. 16 there is shown a modification 25 of the shell shown in Fig. 2, the same in all essential respects except that it shows a piece overlapping on the outside of the line of connection between the two flanges, the purpose of the overlapping strip being to prevent 30 the dirt from forcing itself between the flanges of the shell in the driving operation. The flanges 2^x, 2^x, are formed by two L-shaped pieces welded or otherwise secured to the interior surface of the shell near the 35 edge of its longitudinal division in such manner that the joint between the flanges is away from the joint between the longitudinal edges of the shell, thereby leaving an overlapping strip 3^x. Tongues 4^x on each 40 side are provided to enter pockets 5^x on the opposite side for holding the overlapping strip in place.

In Figs. 23 and 25 are shown two further modifications of the outer shell. In place 45 of one longitudinal division there is a plurality of such divisions, thereby facilitating the removal of the shell from the ground. It will be noticed that in both Figs. 23 and 25 the flanges are so disposed as to make 50 those of each division V-shaped in cross-section, thereby forming wedges, the effect being that after driving the ground outside tends to compress these wedgelike divisions inwardly, but they are held in place by the 55 flanges of the adjoining divisions.

In Fig. 24 is shown a non-expansible mandrel or core for use in connection with the form of shell shown in Figs. 23 and 25. From an open hub portion 67 extend a plurality 60 of open jaws 68. A driving element 69 extends through the hub portion and is bolted securely to the inner ends of two of the jaws 68 and is seated in the shoe 70, as shown in Fig. 27 in cross-section.

65 In Fig. 27 the shoe is shown in whole at

70 and consists of two parts, first an outer shell 71, and, second, an inner half spherical part, removable from the first part, and having a socket 73 for seating the lower end of the driving element 69, and a bore from 70 side to side for a pin 75 connecting the driving element (which has a corresponding bore) with the inner part of the shoe. The outer part 71 has an inside annular groove 76 as a seat for the outside shell. In Fig. 75 26 is a perspective of the whole device except the head, with one section of the outer shell partly removed from the shoe. The driving head and its connections with the driving element are shown in section in Fig. 80 28. The head is shown in whole at 77. Two inside downwardly extending flanges, on opposite sides, 78, are spaced away from the inside of the head to admit the outer shell, and are bored as at 79, 79 to register with 85 similar bores 79', 79' in the head for a pin (not shown) passing through the same and through an opening in the outer shell, to connect and keep the parts firmly together during the driving. On the inside of the 90 head is a rectangular depending strip 80, carrying two transverse pins 81, 81. This strip is bifurcated at its lower end, only one of the bifurcations being shown in the drawing. The driving element is here 95 shown within the dotted lines at 82, where it is shown provided with two slots 83, 83, wherein the pins 81, 81 project and have movement. In the drawings the pins are shown at the top of the slots and the head 100 is in raised position. The object of this arrangement is to permit the head to be raised above the shell when the pins are removed from the bores in the sides of the shell and the head and its inside flanges, thereby giving 105 opportunity for tapping or hammering the shell away from the core.

In Figs. 19 and 20 is shown still another modification of the expansible mandrel, the purpose of which is to drive a short shell. 110 The mandrel itself is in all respects the same as hereinbefore described, except that two additional outer leaves or fillers are added. These fillers 84, 84, are substantially semi-circular in form, and are bolted to the upper end of the outer leaves of the mandrel, by means of holes 85 and bolts 86, to fill up the space on the mandrel that would otherwise be left in driving a short shell. It is important that the bolts should be so located, however, as not to interfere with the movement of the wedges. A space between the fillers, 86, is left to provide for expansion and contraction of the leaves. The short shell 87 is then placed on the lower 115 end of the mandrel, next the shoe 6, and driven in the usual manner.

What I claim is:

1. A pile driving shell adapted to be driven into the ground and there to receive 120 130

- the pile-making material, said shell being divided longitudinally from end to end and having an inwardly extending flange on each side of its longitudinal division, said flanges 5 contacting with each other and having spring action tending to separate them and in the driven position of the shell preventing collapse thereof.
2. An expansible mandrel having inwardly extending coacting gripping jaws adapted to open and close with the expansion and contraction of the mandrel.
3. An expansible mandrel having inwardly and longitudinally extending coacting gripping jaws adapted to open and close with the expansion and contraction of the mandrel.
4. An expansible mandrel comprising a plurality of movable outer leaves, a wedge 20 having an inwardly extending flange to move said leaves, and a pair of inwardly extending coacting gripping jaws adapted to open or close on movement of the outer leaves.
5. An expansible mandrel comprising a plurality of outer leaves, a wedge adapted to positively move the leaves inwardly and outwardly, and a pair of inwardly extending coacting gripping jaws adapted to open or close on each movement of the leaves.
6. An expansible mandrel comprising a plurality of outer sections, wedging means for moving said sections, a driving head connected to the mandrel, and means controlled by the head for positively operating said wedging means to move said sections inwardly and outwardly.
7. An expansible mandrel comprising a plurality of movable sections, a driving head 40 connected thereto, and gravity operating means connected to the head and mandrel for positively moving the sections inwardly when the entire device is lifted by the head.
8. An expansible mandrel comprising a plurality of movable sections and longitudinally and inwardly extending coacting gripping means operated by said sections.
9. An expansible mandrel comprising a plurality of outer leaves, a wedge having an 50 inwardly turned flange adapted to engage and move the leaves, a driving element within the outer leaves, a driving shoe and a driving head connected to said driving element.
10. An expansible mandrel comprising a plurality of sections and a wedge adapted to move the sections and thereby change the diameter of the mandrel, said wedge being slotted parallel with its sides, pins 60 extending from the outer sections into said slots and adapted to assist the wedge in the expansion of the sections on one movement of the wedges and in retracting the same on another movement.
11. An expansible mandrel comprising a plurality of outer leaves one of which is turned inwardly to form one of a pair of jaws adapted to open and close by movement of said leaves, and a compound wedge for moving said leaves consisting of a series of individual wedges cooperating with a corresponding number of wings.
12. An expansible mandrel comprising a plurality of outer leaves, a wedging member for moving said leaves and thereby altering the diameter of the mandrel, said wedging member comprising a series of individual wedges provided with slots arranged parallel to their sides, a series of wings coacting with said wedges, pins connected to the outer leaves and extending into the slots in said individual wedges, whereby downward movement of the wedging member tends to expand the outer leaves of the mandrel and the downward movement of the pins in the slots tends to retract the same.
13. An expansible mandrel comprising a plurality of outer leaves, one or more wedges adapted to move the leaves so as to increase or diminish the diameter of the mandrel, and an inner plate bolted to the outer leaves to secure the wedge in position, said inner plate being provided with slots in connection with the bolt holes to permit movement of the parts.
14. An expansible mandrel comprising a plurality of outer leaves, a wedge adapted to move the leaves, a pair of jaws adapted to open or close on each movement of the leaves, 100 said wedge having a lip extending from the top at right angles to its side, a driving head, and means connected to said lip and said head for lifting the wedge when the mandrel is lifted by the head.
15. An expansible mandrel comprising a plurality of outer leaves one of which is turned inwardly to form one of a pair of jaws and having a right-angled top portion, a second jaw L shaped in cross-section, the 110 jaws in cross-section resembling the letter T, pivotal means for connecting the jaws at their inner ends, and means for operating said jaws with the movement of the outer leaves.
16. An expansible mandrel comprising a plurality of outer leaves one of which is turned inwardly to form one of a pair of jaws and having a right-angled top portion, a second jaw L shaped in cross-section, 120 the jaws in cross-section resembling the letter T, pivotal means for connecting the jaws at their inner ends, and means for operating the jaws with the movement of the outer leaves, and a longitudinally extending member within the outer leaves adapted to act as a driver and also to partially enclose the inner portion of said jaws and thereby keep the parts in position.
17. An expansible mandrel comprising a 130

- plurality of outer leaves one of which is turned inwardly to form one of a pair of jaws and having a right-angled top portion, a second jaw L shaped in cross-section, the 5 jaws in cross-section together resembling a letter T, pivotal means for connecting the jaws at their inner ends, means for operating the jaws with the movement of the outer leaves, a longitudinally extending member 10 within the outer leaves adapted to act as a driver and also to partially enclose the inner portion of said jaws for keeping the parts in position, and adjustable stays connected to the outer leaves and to said longitudinally 15 extending member to assist in holding the parts together. 18. An expansible mandrel comprising a plurality of outer leaves, a wedge adapted to move the leaves, said wedge having a lip 20 extending from its top at right angles to its side, a disk within the top portion of said leaves and under said lip, a driving head and means connecting said disk to said head, a shoe, a longitudinally extending driving 25 member connected to said shoe, and a pin connected to said driving member and said disk so as to permit lost motion, whereby, when the mandrel is lifted by the head, the head, disk and wedge will be the first elements moved. 19. An expansible mandrel comprising a plurality of outer leaves, a wedge adapted to move the leaves, said wedge having a lip extending from its top at right angles to its 35 side, a disk within the top portion of said leaves and under said lip, a driving head and means connecting said disk to said head, a shoe, a longitudinally extending driving member connected to said shoe, a pin connected to said driving member and said disk so as to permit certain lost motion thereof, whereby, normally when the mandrel is lifted by the head, the head, disk and wedge will be the first elements moved, and means 45 for locking the parts against such normal movement. 20. The combination with a driving shell divided longitudinally from end to end with an inwardly extending flange on each side 50 of its longitudinal division and having spring action to normally hold it open, and means for holding the flanges together during the driving operation. 21. The combination of a driving shell 55 divided longitudinally from end to end and
- having an inwardly extending flange on each side of its longitudinal division, and an expansible mandrel comprising a plurality of movable sections, a driving head and a driving shoe, and longitudinally extending means 60 for gripping the flange of the driving shell during the driving operation. 22. A device for withdrawing a longitudinally divided driving shell comprising a collar fitting inside of the top of the driving 65 shell for supporting the latter, means for supporting said collar in position, and a wedge cooperating with the collar in its support of the shell as well as to open the latter. 23. A device for withdrawing a longitudinally divided driving shell comprising a collar fitting inside of the top of the shell for supporting the latter, means for holding the collar in position, guides on said collar, 70 and a wedge within said guides to assist in supporting the shell as well as to open the latter. 24. A device for withdrawing a longitudinally divided driving shell comprising a collar fitting inside of the top of the shell for supporting the latter, means for holding the collar in position, guides on said collar, a wedge within said guides to assist in supporting the shell as well as to open the latter, 75 and a lifting line having a loop and means for supporting the loop on the outside of the top of the shell. 25. The combination with a longitudinally divided driving shell of a lifting device comprising a lifting line having a loop, means for supporting the looped line around the outside of the upper portion of the shell, a collar fitting inside of the top of the shell for supporting the latter against compression by the line, means for holding the collar in position, guides on said collar, and a wedge working in said guides to assist in supporting the shell as well as to open the latter. 26. A driving shell divided longitudinally from end to end, an expansible mandrel therein comprising a plurality of movable outer leaves, a shoe at the lower end of the mandrel having an opening for the passage 105 of means for securing it to the mandrel, and a detachable cap at the lower end of the shell enclosing said shoe and the opening therein and the lower end of the mandrel.

JOHN S. GILLIES.
